COMBINED VALET STAND AND SEAT

John Rolando, Point Lookout, and Robert Z. Lerner, Brookville, N.Y., and Alberto Montina, Udina, Italy, assignors to Stuart M. Lerner, Inc., Melville, N.Y., a corporation of New York

Filed July 15, 1963, Ser. No. 75,794

Term of patent 14 years

(Cl. D33—8)

FIG. 1

FIG. 3

FIG. 1 is a rear perspective view of a combined valet stand and seat showing our design;

FIG. 2 is a front perspective view thereof; and

FIG. 3 is a top plan view thereof, drawn to an enlarged scale.

The unshown side of the article is the same in appearance as the side shown.

We claim:

The ornamental design of a combined valet stand and seat, substantially as shown and described.
